John B. Grotton
WITNESS:

UNITED STATES PATENT OFFICE.

DAVID NORMAN, OF NEW YORK, N. Y.

ATTACHMENT FOR QUILLING MACHINES.

Application filed June 11, 1924. Serial No. 719,385.

To all whom it may concern:

Be it known that I, DAVID NORMAN, a citizen of the United States, residing at New York city, in the county of New York and State of New York, have invented new and useful Improvements in Attachments for Quilling Machines, of which the following is a specification.

This invention relates to an attachment for a quilling machine for the purpose of redrawing imperfect quills or cops.

The principal object of the invention is to provide an attachment which may be used upon quilling machines thereby saving the expense of a separate machine for performing the redrawing of imperfect quills. Heretofore, it has been the practice of redrawing the quills on the bobbin of a winding machine and then removing the same therefrom and placing the quill on the quilling machine.

Another object of the invention resides in the construction of an attachment which may be readily applied to a quilling machine of the type now in use without altering the construction of the machine.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a view in front elevation of a portion of a quilling machine with my attachment applied thereto.

Figure 2 is a vertical transverse sectional view on the line 2—2 of Figure 1.

Figure 3 is an enlarged sectional view of my attachment per se.

Figure 4 is a top plan view of the same.

Figure 5 is a view similar to Figure 3 but showing the parts in reverse position for accommodating a relatively short quill.

It is to be understood that the quilling machine to which my invention is attached, may be operated for performing its quilling operation, simultaneously with the redrawing of defective quills.

Referring more particularly to the drawing, the reference numeral 10 designates a portion of a quilling machine known as the Universal quiller machine and which includes a supporting structure or frame 11 upon which is mounted a plurality of hous-

ings 12. Extending longitudinally through the housings is a main drive shaft 13, on which is mounted a gear 14 for meshing engagement with a gear 15 carried by the end of each driven spindle 16. Driving means 17 is provided for transmitting power to the main shaft 13 and which power is obtained by a belt 18 connected with any suitable power machine.

Supported above the housings and extending the length of the machine is a rod 19 which is square in cross section and which supports the usual bobbin brackets 20 which are arranged in pairs, and the rod also supports tension wires 21 which are provided with eyes 22 at their free ends. The pairs of brackets 20 usually support a full bobbin, but instead, an empty bobbin or removable roller 23 is substituted therefor for a purpose to be presently described.

My attachment is shown in its entirety as at 24 and is slidably mounted upon the rod 19 and includes a cross arm 25 provided with openings 26 for detachably receiving spindles 26, and surrounding each spindle at the bottom thereof is a cup 27. The cross arm 25 is provided with a transverse groove 28 to accommodate a portion of the square rod 19, and in order to render the attachment removable from the rod, there is provided a co-acting cleat 29 having a groove 30 similar to the groove 28 for also accommodating a portion of the rod 19. Bolts 31 pass through the cross arm and enter the cleats for holding the attachment in clamping or adjusted position along the rod as will be readily appreciated.

In operation, the defective quill designated by the letter A is placed upon one of the spindles 26 so that the base of the quill rests in the cup 27 for rotation therein. The end of the silk or thread C carried by the defective quill is passed around the adjacent roller 23 and thence through the eyelet of the tension wire 21 and downward through a porcelain eyelet 32 fastened to the housing, from where it is wound about a clean quill B which is removably secured to the driving spindle 16. It will be seen that as the clean quill B is rotated by means of the spindle 16 through the main drive shaft 13 and gearing 14 and 15, a pull is exerted on the silk or thread and as long as the thread is not broken, the same will continue to wind upon the clean quill B. By passing the lead around the roller and

through the tension wire, a tension is always provided which will prevent the thread from backing up, it being understood that the tension is always the same irrespective of the amount of thread or silk contained on the defective quill. In other words, there is always a steady and even pull regardless of the size of the quill.

Heretofore, it has been the practice to use a winding machine for redrawing quills, but it will be evident that the redrawing or winding may be done with an attachment such as shown upon the well-known type of quilling machine.

The position of the cross bar has been shown in Figures 1 to 4 inclusive in a position for accommodating a relatively long quill, but when a shorter quill is to be redrawn, the cross bar and spindles may be reversed to the position shown in Figure 5 which will raise the quill to the proper height with respect to the roller.

It will be understood that the two quills arranged on the spindles of a single cross arm are operated through opposite sides of the machine, but only the operation of one side has been shown and described as the operation of the other is identical and a further explanation is not deemed necessary. It will also be apparent that any number of quills may be redrawn at a single time depending upon the size of the quilling machine.

While I have described what I deem to be

the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In a device of the class described, the combination with the spindle of a quilling machine, means for driving said spindle, a clean quill mounted on said spindle, a bar supported above said spindle, a full quill adjustable longitudinally upon said rod, a roller mounted adjacent said rod, a tension device above said roller, the thread from said full quill passing completely about said roller and through said tension device for winding the thread on said clean quill at an even rate of speed during the paying out of the thread from said full quill.

2. In combination with the square tension bracket bar of a quilling machine, an arm, spindles rising from said arm, and means for slidably mounting said arm on said bar.

3. In combination with the square tension bracket bar of a quilling machine, an arm, spindles rising from said arm, and means for reversely mounting said arm on said bar for sliding movement thereon.

In testimony whereof I have affixed my signature.

DAVID NORMAN.
